(57) **CLAIM**

(**) Term: **15 Years**

We claim the ornamental design for a tote with a detachable internal pouch, as shown and described.

(21) Appl. No.: **29/670,376**

DESCRIPTION

(22) Filed: **Nov. 15, 2018**

FIG. 1 is a top, front, and right side perspective view of an ornamental design for a tote with a detachable internal pouch;

(51) LOC (13) Cl. **03-01**

FIG. 2 is a front side elevational view thereof;

(52) U.S. Cl. **USPC** **D3/201**

FIG. 3 is a rear side elevational view thereof;

(58) **Field of Classification Search**

FIG. 4 is a right side elevational view thereof;

USPC D3/201, 232, 245, 246, 301, 303
 CPC B65D 29/00; B65D 37/00; B65D 29/04
 See application file for complete search history.

FIG. 5 is a left side elevational view thereof;

(56) **References Cited**

FIG. 6 is a top plan view thereof;

U.S. PATENT DOCUMENTS

FIG. 7 is a bottom plan view thereof;

D265,864 S * 8/1982 Kracke D3/233
 D392,459 S * 3/1998 Jones D3/245
 D403,159 S * 12/1998 Bellechili D3/303
